BREATHING APPARATUS

Christian J. Lambertsen, Philadelphia, Pa.

Application December 16, 1940, Serial No. 370,242

4 Claims. (Cl. 128—142)

My invention relates to breathing apparatus for use under water and in noxious gases, and has for its object to provide means for supplying a limited amount of oxygen carried by a light easily attached harness so that a wearer of the apparatus may descend to very considerable depths of water and remain at such depths for a sufficient length of time to make a proper search for the recovery of bodies of persons drowned or drowning, recover objects and the like.

The apparatus also can be effectively used for similar searching purposes in regions where there are noxious gases such as are found in mines where explosions have occurred, wells, rooms and spaces that have been shut for a long time and rooms and spaces filled with smoke or other unbreathable contaminations following or in connection with fires.

Ordinary diving apparatus requires a regular diving suit and helmet and suitable air pumps for supplying the requisite amount of air to the wearer, also a crew, at least one man to operate the pumps. Such dividing apparatus, from its very nature, cannot be available in the vast majority of cases of need, such as above outlined, particularly in inland regions. My apparatus, however, involving, as it does, only a small outlay for expense and capable of being quickly put on and taken off by the wearer, unassisted by any crew members, and being entirely self-contained in the supply of oxygen, is well adapted to meet the general need which cannot be supplied by regulation diving apparatus.

It is a particular object of my invention, therefore, to provide a breathing unit adapted to supply oxygen which has mounted on a harness structure easily applied to the body all of the elements necessary to supply oxygen to the wearer in a closed breathing circuit.

Inasmuch as the circuit, except for a small amount of escape of exhalations, is closed, I also provide means for permitting full exhalation and inhalation, and it is an object of my invention to provide such means so related to the pressure at any depth to which the wearer may go as to maintain the breathing at a properly adjusted pressure.

It is a further object of my invention to cause the gases which are inhaled and exhaled to pass through means for withdrawing from it its carbon dioxide content, specifically a reservoir of carbon dioxide absorbing material, such as soda lime.

It is a further object of my invention to provide means for carrying a supply of oxygen and

for delivering it in a suitably regulated stream to a point within the breathing line where the pure oxygen will be suitably mixed with re-breathed gases and at the same time go to the breather in an effective form and build up an advance charge of oxygen at the end of exhalation to be taken into the lungs immediately upon restoring inspiration.

It is a further object of my invention to mount all of the various instrumentalities upon a harness adapted to slip over the upper part of the body and to be easily attached thereto, in conjunction with a breathing mask made watertight, and with an exhaling valve that is watertight, and which mask is adapted to be held upon the face of the wearer.

The full objects and advantages of my invention will appear in connection with the detailed description thereof and its novel features by which the above noted advantageous results are secured will be particularly pointed out in the claims.

In the drawings illustrating an application of my invention in one form:

Fig. 1 is a front elevation view showing the apparatus as worn.

Fig. 2 is a similarly disposed rear view.

Fig. 3 is a side sectional view through the breathing apparatus.

Fig. 4 is a sectional elevation view through the reducing valve for delivering oxygen from a compressed oxygen tank to the breathing line.

Fig. 5 is an enlarged sectional view showing the means of connecting the breathing tube to the reducing valve.

Fig. 6 is a sectional view taken on line 6—6 of Fig. 3.

Fig. 7 is a sectional view taken on line 7—7 of Fig. 6.

Fig. 8 is a sectional view through one of the re-breathing bags and the tube leading thereto.

Fig. 9 shows a modified form of re-breathing bag and oxygen supply and means of securing the absorber container in the system.

Fig. 10 is an enlarged view partly in section showing the manner of connection of the reducing valve to the compressed oxygen tank.

As illustrated, a supporting harness is provided comprising a front plate 10 to which is secured shoulder straps 11 and 12 connected by a breast strap 13. The shoulder straps 11 and 12 are further connected by a back strap 14 leaving an ample opening between shoulder straps 11 and 12 and between breast strap 13 and back strap 14. The shoulder straps 11 and 12 are continued

below plate 10 in extensions 15 and 16, Fig. 1, which are secured to a waistband strap 11 adapted to be secured around the waist of the wearer by an end tab 18 passing through a buckle 19, Fig. 1. The shoulder straps 11 and 12 are also at their back secured to the waistband 17.

A second back strap 20 is secured to the shoulder straps 11 and 12, Fig. 2. This has portions 21 and 22 which extend beyond the respective margins of the shoulder straps 11 and 12 and are secured to tabs 23 and 24 depending from the shoulder straps 11 and 12 adjacent their points of union with the back strap 14.

A pair of rebreathing bags 25 and 26, Fig. 2, are connected by tubes 27 and 28 that pass under the arms of the wearer, as shown, with apparatus later to be described, at the front of the harness, and the upper end of these tubes and the rebreathing bags 25 and 26 are in turn supported by clamp members 29 and 30 surrounding the tubes and secured to the tabs 23 and 24, as shown in Fig. 2.

Details of the rebreathing bag are shown in Fig. 8 wherein a union 31 receives the neck 32 of the rebreathing bag, and the clamp 30 (or 29) locks the tube and rebreathing bag to the tab 24 by means of the bolt 33. The rebreathing bags are thus secured in normal position at the back of the wearer out of the way and yet in free communication through tubes 27 and 28 with the breathing passages and inhalator later to be described. If desired the rebreathing bag 26 might be internally reinforced by a suitable supporting cage, but in practice I have not found that necessary. I provide a tube 34 secured to the union 31 which extends up into the rebreathing bag and is provided with a suitable number of side perforations 35 and a top perforation 36.

As shown in Fig. 1, the tubes 27 and 28 are secured by clamps 37 and 38 to the waistband 17 and are connected together by a T-union 39. The union 39 is connected by a tube 40 with the centrally opening neck 41 of a casing 42 which is secured by a clamp 43 to the plate 10. The casing 42 is provided with a central nipple 44 forming an outlet opening 45. Within the chamber 46 of casing 42 are perforated partitions 47 and 48. Upon partition 48 rests a body 49 of absorbent material such as soda lime. It will be noted that the end plates 50 and 51 of casing 42 are conical in shape so there are spaces 52 and 53 above the perforated partition 47 and below partition 48 respectively.

Secured to nipple 44 is a main breathing tube 54 preferably corrugated and which may be reinforced by metal rings 55, Fig. 3, to certainly guard against collapse. The tubes 27 and 28 may be similarly corrugated and reinforced. The tube 54 is connected to union 56 and in turn the union 56 is connected to an outlet tube 57 of a mask 58. The mask 58, as shown in Fig. 3, is provided with face-engaging flap members 59 and 60, which under pressure will normally seal the breathing chamber. Further, the mask is additionally secured in place by sets of tapes 61 and 62 running across the front of the mask and secured at the back of the neck, as indicated at 63 of Fig. 2, and in addition a top band 64 connects the top of the mask at 65 and runs over the head of the wearer as indicated at 66 and is secured by a buckle 67 with a second tab 68 fastened at 69 to the back band 63. With this form of mask the nose and mouth of the wearer are encased in a chamber 70 opening directly below

the nose through the passageway 71 through tubular extension 57.

An exhaling valve 72, shown in detail in Figs. 6 and 7, is united at 73 with the union 56. This exhaling valve 72 is provided with a nipple extension 73 which is threaded into an extension 74 of the coupling 56, as shown in Fig. 3. I do not claim the structural features of this exhaling valve as my invention and have illustrated it here for the purpose of showing its operation in the combination which does constitute my invention.

The valve 72 is provided with a cap 75 threaded as indicated at 76 upon a cylindrical member 77, Fig. 7, there being thus formed a chamber 78 within the space limited by the cap 75 and the threaded extension 77. A boss 79 is held in engagement with the top 80 of the cap 75, and surrounding this boss is a compression spring 81 which engages a flange portion 82 surrounding the top of boss 79. The boss 79 has a threaded portion 83 extending through an opening 84 in the cap top 80 and is secured in position by a nut 85 threaded on said extension 83.

Across the opening 86 within nipple extension 73 is positioned a perforated disc 87 and held to float freely within the threaded extension 77 is a disc 88 of highly flexible material such as lastex, which is adapted, on inhalation, not only to seal against the raised valve seat edge 88, but also to seal against the perforated disc 87, thus giving a much larger sealing area than is true of the customary valve, sealing against a single annular ridge. The flexible disc 88 is held against the valve seat 88 by contact with the face of a disc member 140 having a stem 141 passing through an aperture in the center of boss 79. The degree of pressure of the spring may be varied as desired by means of the cap 80 which carries on its face a series of calibrations ("9" to "13," as given) designated by the numeral 143, Fig. 6. The calibrations are adapted to register with a pointer 144 fast on the extension 74. It is also true that the spring 81 is of a diameter such that it exerts its pressure directly above the annular edge 88, thus additionally insuring effective sealing action. The extension 77 is provided with a multiplicity of laterally opening apertures 90 for permitting discharge of a certain small percentage of exhaled air.

It will be apparent from the above description that breathing, so far as inhalation goes, must come from entirely within the system, since the exhaling valve structure, above defined, is such as to instantly shut off any ingress of fluid through the valve, which of course it must do when the apparatus is submerged in water. It follows that for maintaining life a supply of oxygen must be introduced into the breathing passage.

To effect this a tank 91 containing a suitable amount of compressed oxygen is held in a stirrup 92 which is secured to loops 93 and 94, in turn fastened respectively upon the straps 22 and 17. A buckle strap 95 secures the tank 91 in the pocket thus formed. A valve 96 positioned at the top of tank 91 is adapted to be opened after the apparatus has been put on, being conveniently positioned for reach of the hand over the shoulder.

Secured to a connector 97 extending from the neck 98 of tank 91 is a reducing valve 99 which is provided with a duct 100, Fig. 10, leading therefrom. This duct leads to a chamber 101, Fig. 4. A second chamber 110 is closed by a

flexible diaphragm 102 engaged by a follower 103 contacted by a strong compression spring 104. A valve disc 105 in chamber 101 is adapted to engage a valve seat 106 and has connected therewith a pusher pin 107 which engages the diaphragm 102 and follower 103 so that the pressure of spring 104 tends to push the valve plate 105 away from the valve seat 106 and permit flow of gas to chamber 110, through passages 111, from whence it may feed through port 108 and chamber 109 to delivering tube 113. The pressure of the gas upon diaphragm 102 will counteract the pressure of spring 104 and cause the gas to be delivered to tube 113 at a suitably predetermined reduced pressure in a well known way.

The oxygen tube 113, as clearly shown in Fig. 1, is held by a clamp 114 to breathing tube 28 and is connected at 115 with a connector tube elbow 116 which makes a right angle turn in passageway 56, Fig. 6. To the elbow connector 116 is secured a flexible tube 117 which has its end 118 close to the opening 86 into the inhaling valve 72. An opening 119 is also provided in the side of tube 117.

As shown in detail in Figs. 4 and 5, particularly in Fig. 5, chamber 109 in valve block 120 is provided with a threaded opening 121. Within the opening 121 is screwed an externally threaded extension 122 of a connector block 123, to the end of which the delivery tube 113 is secured, the connector block being formed with a nut portion 124, as clearly shown. The extension 122 is provided with a chamber 125 in which is a block 126 formed with a threaded boss 127 which is screwed into an internally threaded central opening 128 in the block 123. A small aperture 129 leads centrally through the block from chamber 125 and connects with a larger aperture 130 which in turn connects with aperture 131 leading through to the inside of tube 113. The aperture 129 constitutes a limit port, which controls the rate of flow of oxygen at the delivery pressure set so as to deliver the proper volume of oxygen into the breathing line. A sealing washer 132 is engaged by block 126. A filter pad 133 closes the top of chamber 125 between it and chamber 109 thus filtering all oxygen which passes into the breathing line to prevent dust or metal flakes passing to the lungs.

In place of the rebreathing bag arrangement shown in Fig. 1, a variant for use in toxic atmospheres is illustrated in Fig. 9, whereby the casing 43 is directly connected to shoulder straps 11 and 12 by a metallic clamping member 134. From the lower end of the casing 43 is suspended a rebreathing bag 135. The oxygen tube 113 is carried downwardly to the bottom of bag 135, as indicated at 136.

The advantages of my invention will be apparent from the foregoing description thereof. The construction can be donned with extraordinary rapidity, it being necessary only to put together and pull up three buckle strap members 18-19, 63 and 67, then turn on the oxygen through manipulation of knob 96 and the apparatus is ready for use either for a descent under the water or for movement into a space filled with noxious vapors. Owing to the fact that the flexible breathing bags are subject to the same pressure as is the chest and body of the wearer, breathing will in effect be at normal pressure; that is, the internal and external pressures on the lung cavity will be balanced at whatever depth in the water the wearer may go.

The entire arrangement is one of balance. Normally it will be adjusted in weight so that when submerged its buoyancy balances its sinking tendency. However, obviously weights can be added to permit walking under a body of water where desired.

The breathing of the wearer is normal and comfortable. Although the face and eyes and ears are exposed as shown, obviously protectors covering the eyes and ears may be employed if that is desirable. In breathing, exhalation will take place normally to fill the rebreathing bags, to be followed by some exhaust through the exhalation valve 72 of those gases most heavily charged with carbon dioxide. The exhalation going to the rebreathing bags will meet the stream of oxygen coming from the end 118 and side opening 119 of tube 117 and will carry some of said oxygen along with it through the absorber material 49 where carbon dioxide will be removed. The resulting mixture in the rebreathing bags and as it comes to the wearer's lungs will contain an amount of oxygen in excess of that required for the needs of the wearer under the most severe conditions of exertion, yet there is substantially no waste of oxygen so the amount of oxygen available from the compressed oxygen tank carried by the apparatus will serve for a maximum length of time.

Upon inhalation the exhaling valve will instantly close, a small amount of carbon dioxide will go back into the lungs from the upper part of the breathing passage for respiration stimulus, and the gas mixture from the rebreathing bags with added oxygen constantly flowing from tube 117 will be taken into the lungs. This operation may be repeated as long as the supply of oxygen from tank 91 is available. Obviously the length of time which the apparatus may be used may be varied as conditions require by varying the size of the oxygen tank 91. The exhaling valve is not only adapted to operate so as to expel exhalation most heavily charged with carbon dioxide, but this also relieves excess pressure within the system from over-distension of the rebreathing bags. Further, when the apparatus is employed under water the exhaling valve, while permitting escape of exhalation, will absolutely seal against inlet of water upon inhalation or when breathing is not taking place.

As above pointed out the harness is particularly adapted for rapid and simple donning and is designed to fit individuals of different sizes and shapes. The position of the rebreathing bags at the shoulders of the wearer keeps them from interfering with the movements of the wearer and at the same time gives quick response to the wearer's breathing, the large tubular passageways running from the rebreathing bag being particularly effective for permitting ready flow of breathing gases to and from the rebreathing bags. The breathing tube from the soda lime container is reinforced with metal rings to prevent any tendency for collapsing upon inhalation. The plate to which the soda lime container is attached is preferably formed of lead to give some needed weight to the apparatus for descending under the water.

The entire arrangement is such as to be comfortably and easily worn leaving the body of the wearer entirely unhampered. The breathing arrangement is such that adequate oxygen is supplied freed from undesirable quantities of carbon dioxide for periods of time determined by the size of the oxygen-containing tank, which

also operates as a weight for aiding the wearer to descend to desired depths in the water, and, taken in connection with the lead plate and absorber casing at the front of the body, produces a balanced distribution of weight under the water.

While a principal use of the apparatus is in connection with searches and work under water, it is obvious that it can be used for respiration in any space where there is toxic or poisonous gases or deficiency of oxygen. Although the apparatus can be used in exactly the form adapting it for use under water, the modification of Fig. 9 may be employed in atmosphere where water pressure and buoyancy does not require balance of arrangement and of weight distribution, which, however, are essential for use of the apparatus at any considerable depth of water.

I claim:

1. Breathing apparatus for use under water and in noxious gases, comprising a harness having front and rear portions and adapted to be readily secured on the upper part of the body, a mask with means for securing the mask upon the face of a wearer so as to be gas-tight and water-tight, a breathing tube secured to the front of the harness, a pair of extensions from said breathing tube running around and to the back of the harness, a rebreathing bag supported by each of said extensions at the back of the harness, an oxygen tank removably carried, in a vertical position as worn at the center of the back of the harness, means for supplying a regulated volume of oxygen to the breathing tube, and an exhalation valve for permitting escape of some exhalation gas against water pressure and automatically sealing against such pressure upon inhalation.

2. Breathing apparatus for use under water and in noxious gases, comprising a harness having front and rear portions and adapted to be readily secured on the upper part of the body, a breathing tube including therein a casing holding a body of carbon dioxide absorbent material such as soda lime supported at the center of the front of the harness, a mask with means for securing the mask upon the face of a wearer so as to be gas-tight and water-tight having breathing connection with said breathing tube, a pair of extensions from said breathing tube running around and to the back of the harness, a rebreathing bag supported by each of said extensions at the back of the harness, adjacent

the shoulders when the harness is in position on a wearer, an oxygen tank removably carried, in a vertical position as worn at the center of the back of the harness, and means for supplying a regulated volume of oxygen to the breathing tube.

3. Breathing apparatus for use under water, comprising a harness having front and rear portions passing over the shoulders and held in position to be readily removed and applied to the body of the wearer by a belt adapted to be secured around the waist of the wearer, a mask removably secured in sealing relation upon the face of the wearer, a breathing tube connected with the mask and including an expanded casing forming a chamber holding a body of carbon dioxide material such as soda lime, said breathing tube and casing secured along the vertical central front of the harness, a rebreathing bag secured to the back of the harness and having connection with the breathing tube below the absorber casing at the belt of the wearer, an oxygen tank removably supported along the vertical center of the back of the harness, an exhalation valve opening into a breathing tube close to the mask, and an oxygen supply tube extending from the oxygen tank into the breathing tube above and close to the absorber casing and extending through the breathing tube to discharge oxygen close to but below the exhalation valve.

4. Breathing apparatus for use under water, comprising a harness having front and rear portions passing over the shoulders and held in position to be readily removed and applied to the body of the wearer by an adjustable belt passing around the waist of the wearer, a weighted plate secured to the front part of the harness above the belt, a carbon dioxide absorber casing secured to said plate at the center of the front of the harness, a mask sealed on the face of the wearer, a breathing tube extending therefrom and connected on each side of the absorber casing, a rebreathing bag supported at the back of the harness and having connection with said breathing tube below the absorber casing, an oxygen tank removably carried at the center of the back of the harness, and means for delivering oxygen from the tank to the breathing tube above the absorber casing, the arrangement of tank and plate and parts carried by the plate being relatively such as to give balanced distribution of weight.

CHRISTIAN J. LAMBERTSEN.
